UNITED STATES PATENT OFFICE.

EDWARD B. GARDNER, OF BELOIT, WISCONSIN, ASSIGNOR TO BADGER TOOL COMPANY,
OF BELOIT, WISCONSIN, A CORPORATION OF WISCONSIN.

WHEEL-DRESSING MEANS FOR GRINDING-MACHINES.

1,320,752.

Specification of Letters Patent.

Patented Nov. 4, 1919.

Original application filed September 21, 1918, Serial No. 255,022. Divided and this application filed February 20, 1919. Serial No. 278,227.

To all whom it may concern:

Be it known that I, EDWARD B. GARDNER, a citizen of the United States, residing at Beloit, in the county of Rock and State of Wisconsin, have invented certain new and useful Improvements in Wheel-Dressing Means for Grinding-Machines, of which the following is a specification.

This invention relates to the art of grinding machines, and the general object of the invention is to provide an improved work table and means thereon for dressing the grinding wheel.

A special object is to provide a wheel dressing device which is small and compact, and to provide means for mounting the device on the work table in such a way that the device may remain on the work table at all times ready for use, and yet will not interfere with the attaching of the work to the grinding table or with the grinding operation.

In the accompanying drawings Figure 1 is a side elevation view of so much of a grinding machine as is necessary to an understanding of my invention. Fig. 2 is a sectional plan view through the work table taken in the plane of line 2—2 of Fig. 3. Fig. 3 is a rear end elevation of the table with certain stop devices sectioned away. Figs. 4, 5 and 6 are, respectively, a plan view, and inner and outer side elevations, of the wheel dresser demounted.

The exemplary machine to which I have herein shown the invention as applied is of the type known as a disk or ring wheel grinder. Briefly described, the machine comprises a body, of which a fragment is indicated at 11, and a grinding wheel 12 fixed on the end of a shaft, not shown, which is revolubly mounted in the body. A bar 13 projects from the body beneath the grinding wheel and constitutes the means on which the work support as a whole is mounted. A rocker box 14 is mounted on the bar 13 and has a slot or groove in which an upright bar 15 is slidably mounted, the bar 15 being held in different positions by

means of set screws 16 to support the work table at different elevations. A counter-weight 17 is fixed to the lower end of a rod 17^a which is fixed to and depends from a sleeve portion of the rocker box 14.

The work table comprises a base or support 18 having a downwardly extending lug 19 overlapping a portion of the upper end of the bar 15, being pivoted at 20 thereto and having an arcuate slot 21 through which passes a screw or bolt 22 that is seated in the bar for clamping the parts together in any desired position of angular adjustment.

The work table further comprises a table top 23 slidably mounted on the support 18 to move toward and away from the grinding wheel 12. Any desired means may be employed for sliding the table top 23, that herein shown comprising a shaft 28 having a crank 27 fixed on its upper end, the free end of which crank is connected by a link 26 to the table top, said crank and link lying between said top and the support 18. On the lower end of the shaft 28 is fixed a hand lever 29. A stop screw 45 mounted in the table top 23 is arranged to abut against the base 18 of the table to limit the motion of the table top 23 toward the grinding wheel 12. A rod 46 seated in the base 18 and passing slidably through the end of the table top carries a stop 47 to limit the motion of the table top away from the grinding wheel. This means for sliding the table top forms the subject matter of my copending application for patent, Serial No. 255,022, filed September 21, 1918, of which this application is a division.

The work to be ground is fixed to the upper face of the table top by any suitable means such as bolts 24, the heads of which engage in undercut slots 25 in the table top.

The wheel dressing means is mounted on the slideable table top in a position beneath the plane of the upper face of said top and in such a manner that the dresser device may be readily adjusted to operative or inoperative position at will, that is to say, to a position projecting beyond the for-

ward end of the table top or a position rearward from such forward end. The piece of work which is secured to the table top by means of the bolts 24 is frequently of such size that it projects beyond the side edges of the table top and for this reason the wheel dresser is attached beneath the plane of the top face where it will not, at any time, interfere with the work and yet will 10 always be ready for use.

While the wheel dressing member may be of any one of the well-known types, I have herein shown it as consisting of a roller to contact with the grinding wheel, 15 although it should be understood that the other kinds of dressing members may be employed.

Referring now to the particular construction of dressing means which is herein 20 shown by way of example, and to the exemplary means for attaching the dressing means to the table top, it will be noted that the device comprises a support in the form of a bracket 40 which is bifurcated to receive a wheel dressing roller 41 of suitable construction, the roller being mounted on a pin or screw 44 seated in the spaced arms of the bracket.

The wheel dresser may be mounted in 30 different positions on the table top so long as it is kept beneath the plane of the upper face thereof, but I have found it most convenient to attach the device to one of the vertical side faces of the table top. The preferred manner of attachment is to provide the table top with an undercut slot 39, and to provide the bracket 40 with a rib 42 to enter the narrow portion of said slot, the bracket being adjustably attached to the 35 table top by means of a bolt 43 passing through a hole in the bracket and having its head engaging in the wider part of the slot 39, the bolt having a nut on its outer end for clamping the bracket in any desired 40 position on the table top.

When the grinding wheel 12 is to be dressed the dressing device is secured in the position shown in Fig. 2 so that the dresser wheel projects beyond the end of the table 50 top. The hand lever 29 is then moved toward the grinding wheel to press the dresser roller with the desired degree of force against the grinding wheel. The wheel dresser may be caused to pass approximately 55 radially across the face of the grinding wheel by swinging the work table back and forth on the supporting bar 13 as an axis, so that all points on the grinding wheel will be dressed.

60 When not in use the wheel dresser is secured in a position rearward from the front end of the table, in which position the device will not, in any way, interfere with the securing of a piece of work on the table top

even though the work project beyond the 65 edges of the table, because the device is located beneath the plane of the upper face of the table top 23. The wheel dresser is also of small dimensions so that it is not in the way during the grinding operation. 70

The particular details of construction of my invention have been herein described for the sake of lucidity only and not with any intention of limiting the invention to the exact structure disclosed. The scope of the 75 invention is pointed out in the appended claims.

I claim as my invention:

1. A work table for grinding machines equipped with means for securing a piece 80 of work to the top face of the table, in combination with a wheel dresser, and means for adjustably securing said wheel dresser to the work table in a plane beneath said top face. 85

2. A work table for grinding machines equipped with means for securing a piece of work to the top face of the table, in combination with a wheel dresser, and means for adjustably securing said wheel dresser 90 to one of the upright side faces of the work table. 95

3. A work table for grinding machines equipped with means for securing a piece of work to the top face of the table and having a horizontal slot located in a plane beneath said top face, in combination with a wheel dresser and means to engage in said slot for securing the wheel dresser to the table, said wheel dresser being adjustable 100 along said slot to project beyond the front end of the table so as to engage the grinding wheel or to occupy a position rearward from the front end of the table. 105

4. A work table having an undercut slot 105 therein, and a wheel dresser device having a bolt to engage in said slot for clamping the device to the table, said device lying below the plane of the top of the table.

5. A work table having, in combination, 110 a wheel dresser, and means for adjustably fixing said dresser to one side of the table.

6. A work table having an undercut slot 115 therein, a bracket carrying a wheel dressing roller, means on said bracket engaging said slot to permit sliding of said bracket and prevent rotation thereof, a bolt passing through said bracket and having a head engaging in the undercut portion of the slot, and a nut on the outer end of said bolt arranged to clamp said bracket in different 120 positions on the table, said bracket and wheel occupying a position beneath the upper face of the table.

7. A work table having, in combination, 125 a support, a table top slidably mounted thereon, means for moving said top, and a wheel dresser adjustably fixed to one side

of said table top in a plane beneath the upper face of said top.

8. A work table having, in combination, a support, a table top slidably mounted thereon, means for moving said top, the top having means on its upper face to permit of clamping the work thereto, and a wheel

dresser adjustably mounted on one face of the table top in such position that it does not interfere with the clamping of the work 10 on the table top.

In testimony whereof, I have hereunto set my hand.

EDWARD B. GARDNER.
